[57] ABSTRACT

An arrangement for feeding the power winding of an electromagnet with rectified A.C. by means of a thyristor or triac. The latter is inserted in parallel with a transistor the conducting condition of which is provided by a condenser fed by the rectified A.C. and discharging into the base of the transistor which latter acts then on the electrode controlling the thyristor, to allow the latter to return into its non-conductive condition at the end of an alternation. A maintenance or holding current is provided either through an auxiliary electromagnet winding or through a chopped current feeding the power winding and produced by a pulse generator.

FIG. 1

FIG. 2

ELECTROMAGNET-CONTROLLING SYSTEM

The present invention covers an arrangement controlling an electromagnet and adapted to supply upon energization a strong initial current, followed by a weaker maintenance current. Such an arrangement allows in particular the electromagnet to exert a larger initial attraction without exaggeratedly heating its winding, since the maintenance current following the initial current is comparatively weak.

The control arrangement comprises, according to the invention, a Graetz rectifier connected with a supply of A.C. and feeding an electromagnet winding in series with a thyristor, the control electrode and the cathode of which are connected with each other through delaying means which become conductive at a predetermined moment following the closing of a control switch.

In the accompanying drawings:

FIGS. 1 and 2 illustrate diagrammatically and by way of example two embodiments of the arrangement forming the object of the invention.

As illustrated in FIG. 1, a rectifier 1 operating on both alternations is connected through a switch S with the terminals *a* and *b* fed by a supply of A.C., e.g. the mains.

The controlled electromagnet includes two windings B_1 and B_2 , the maintenance winding B_2 being fed directly across the terminals *c* and *d* of the rectifier 1. The power winding B_1 is connected across said output terminals of the rectifier, in series with a resistance R_2 and a transistor T_1 . Said winding B_1 is also connected with the negative output terminal *d* of the rectifier through a thyristor T_2 in series with two diodes D_1 and D_2 .

The base of the transistor T_1 is connected with a condenser C through a Zener diode Z . This condenser C forms with the resistance R_1 and RC element. The base of the transistor T_1 is connected with its emitter through a leak resistance R_3 . The power winding B_1 is shunted by a diode D_3 .

The operation of the arrangement is as follows:

The closing of the switch S obviously energizes the winding B_2 . The winding B_1 is also subjected to a positive voltage since the transistor T_1 is non-conductive at the start; in fact the control electrode of the thyristor T_2 is practically subjected to the voltage of the positive terminal *c* of the rectifier, whereas the cathode of said thyristor is substantially at the voltage of the terminal *d*. The thyristor T_2 is therefore conductive, so that the power winding B_1 is fed.

The condenser C is loaded gradually through the resistance R_1 and when its voltage reaches the threshold voltage of the Zener diode, said voltage is applied on the base of the transistor T_1 which becomes conductive.

The control electrode of the thyristor T_2 returns then to the voltage of the terminal *b* and is therefore negative with reference to the cathode of the thyristor by reason of the drop in voltage by about 2 volts across the diodes D_1 and D_2 . Since the drop in voltage across the transistor T_1 is about 0.5 V, the control electrode is biased negatively by about 1.5 V with reference to the cathode of the thyristor T_2 . The thyristor is therefore under conditions which make its extinction an easy matter during the next passage through zero of the rectified current fed by the rectifier 1.

After extinction of the thyristor T_2 , the winding B_1 is no longer fed and only the maintenance winding B_2 remains operative. It should be remarked that the diode D_3 cuts out all overvoltages in the winding B_1 during said extinction of the thyristor T_2 .

Of course, many modifications may be brought to the circuit described and in particular it is possible to replace the Zener diode Z by any other component provided with a threshold voltage beyond which it becomes conductive.

The embodiment illustrated in FIG. 2 distinguishes from the first embodiment through the absence of an auxiliary maintenance winding B_2 for the electromagnet. The circuit feeding the winding B_1 is identical with that of FIG. 1 except for a resistance R_4 inserted between the collector of the transistor T_1 and the control electrode of the thyristor T_2 .

In this second embodiment, a pulse generator 2 provides the application to the control electrode of the thyristor T_2 , of pulses synchronized with the frequency of the mains and phase-shifted with reference to the latter. Thus, when the transistor T_1 becomes conductive and prevents consequently the automatic ignition of the thyristor T_2 , the latter is rendered conductive during each alternation by the pulses supplied by the generator 2. Thus, there is obtained a chopped current, the average value of which is lower than that of the current obtained at the start. Said chopped current forms the maintenance current for the electromagnet.

The pulse generator comprises, as well-known per se, a single-junction transistor T_3 fed through a resistance R_5 and across a Zener diode Z_2 . The voltage across the terminals of said diode Z_2 is applied to the base of the transistor T_3 through a resistance R_6 which loads a condenser C_2 . Each time the voltage across the terminals of said condenser reaches the threshold value of the transistor T_3 , the latter becomes conductive and allows the passage through a resistance R_7 of a current which produces a voltage pulse which is applied to the control electrode of the thyristor T_2 .

An important advantage of the circuits described resides in the fact that, whatever the voltage of the mains may be, the voltage to which the transistor T_1 is subjected never rises above a few volts, since for a voltage of this magnitude, the thyristor T_2 becomes immediately conductive.

It is of course possible to bring numerous modifications to the wiring diagrams described and, in particular, the thyristor T_2 may be replaced by a triac. In such a case, the pulse generator 2 may be provided so as to supply pulses of a negative polarity while the diodes B_1 and D_2 may be omitted.

I claim:

1. An electromagnet-controlling system adapted to produce a strong starting current for an electromagnet power winding followed by a weaker holding current comprising a Graetz rectifier, adapted to be fed with A.C., a thyristor circuit including an anode and a cathode inserted in series between the rectifier and the electromagnet power winding and a controlling electrode, and delaying means inserted between said cathode and controlling electrode and adapted to become conductive at a predetermined moment after energization of the rectifier to allow the thyristor circuit to return to its inoperative condition and means feeding a weaker holding current to the electromagnet.

2. A system as claimed in claim 1, wherein the delaying means include a transistor, the emitter-collector circuit of which is inserted in parallel with the thyristor circuit and is connected with the controlling resistance of the latter, a resistance and condenser circuit fed by the rectifier and an element provided with a threshold voltage and operatively connecting said condenser with the transistor base as soon as the condenser voltage has reached a predetermined voltage.

3. A system as claimed in claim 1, wherein the delaying means include a transistor, the emitter-collector circuit of which is inserted in parallel with the thyristor circuit and is connected with the controlling resistance of the latter, a resistance and condenser circuit fed by the rectifier and an element provided with a threshold voltage and operatively connecting said condenser with the transistor base as soon as the condenser voltage has reached a predetermined voltage, and at least one diode inserted between the negative terminal of the rectifier and the cathode of the thyristor circuit and leading the current passing out of the latter towards

said negative terminal.

4. A system as claimed in claim 1, wherein the means feeding the holding current include an auxiliary holding winding inserted across the rectifier terminals in parallel with the power winding and thyristor circuit.

5. A system as claimed in claim 1, wherein the delaying means include a transistor, the emitter-collector circuit of which is inserted in parallel with the thyristor circuit and is connected with the controlling resistance of the latter, a resistance and condenser circuit fed by the rectifier and an element provided with a threshold voltage and operatively connecting said condenser with the transistor base as soon as the condenser voltage has reached a predetermined voltage and wherein the means feeding the holding current include a generator of pulses synchronized with the frequency of the A.C. fed to the rectifier and phase-shifted with reference thereto and means for applying said pulses to the thyristor circuit.
